UNITED STATES PATENT OFFICE.

EDWARD D. SMITH, OF ERIE, PENNSYLVANIA.

COIN RETAINER.

Application filed February 1, 1923. Serial No. 616,387.

To all whom it may concern:

Be it known that I, EDWARD D. SMITH, a citizen of the United States, residing at Erie, in the county of Erie and State of Pennsylvania, have invented new and useful Improvements in Coin Retainers, of which the following is a specification.

The invention is designed to act as a savings coin retainer. As formed a coin pocket is arranged in a part of a removable cover for a bank pass-book. In carrying out the invention in its preferred form the coin receiving pocket is sealed by a renewable seal which is broken by the bank and renewed as the accumulated coins are deposited. Features and details of the invention will appear from the specification and claims.

The invention is illustrated in the accompanying drawings as follows:—

Fig. 1 shows a view of the blank from which the cover is made.

Fig. 2 a view of the coin retainer with the pass book in place, the coin retainer and pass book being open.

Fig. 3 a front elevation of the coin retainer showing the pass book title.

Fig. 4 a detached perspective view of the non-return flap of the coin pocket.

Fig. 5 a side view of the same.

1 marks the pass book having the permanent covers 2. The covers of the pass book are inserted in pockets in the coin retainer, one pocket being formed in a flap 3 which extends from a fold 4, the back being formed by the turning over and securing the flaps 5, 6 and 7. The flap 8 has the extension folds 9 and 10, the fold 10 being folded on the fold 9 and the combined fold being folded on the flap 8, thus forming a pocket 11 in which the cover of the pass book is placed thus securing the pass book in the coin retainer, the top and bottom of this pocket being closed by the folds 12 and 13 at the bottom and top of the flap 8.

The cover 8 has an opening 14 which exposes the face of the pass book showing a title as at 15 in Fig. 3.

The fold 9 which is the inward face of the coin pocket is provided with slits 16 for receiving and securing a non-return device which operates in conjunction with a coin slot 17 in which a coin A is shown as being inserted.

The non-return device is formed of a strip of paper having the two folds 18 and 19 and these folds have the return

bends 20 and 21, the edges of which are in engagement. The folds tend to press their edges together. When this non-return device is slipped into the slit 16 it brings the 60 crease 20^a of the fold 20 just below the coin slit 17 so that a coin deposited through the slit passes down between the folds 20 and 21 and out between their edges into the portion between the folds 18 and 19. With 65 an attempted return movement of the coin the edges of the folds 20 and 21 are more closely pressed into contact than are these edges in contact with the folds 18 and 19. As a consequence when the coin slips upwardly if the container is reversed it simply passes into the space between the folds 18 and 21 or 19 and 20 and is arrested at the crease of the fold.

In order to readily remove the coins and 75 also the non-return insert I preferably provide a gummed slip 23 which extends through the slit 16. As the non-return device is inserted through the slit 16 the gummed label is slipped into the lower slit 80 16 and sealed down. When it is desired 85 to remove the coins this gummed label is cut and the non-return device is withdrawn carrying with it the deposited coin. If desired a record of the coins placed in the retainer may be placed on the gummed label at 90 24. Inasmuch as this is renewed with each deposit a new record is thus provided, it being understood as the bank replaces the non-return device a fresh gummed label is in 90 each instance provided.

It may be desirable to hold the edge of the fold 21 away from the fold 18 so that the inserted coins may fill in the entire space. This is accomplished by the fold 95 corners 22 which hold the edge of the fold 21 slightly away from the fold 18.

What I claim as new is:—

1. In a coin retainer, the combination of a pocket formed of enclosing flaps having 100 a coin-receiving slit; a non-return flap in the pocket, said flap being yieldable to permit the introduction of a coin passed into the pocket and interposed to prevent a return movement of the coin to the slit; and a sealing device for the non-return flap in the form of a renewable gummed leaf, the gummed leaf having a coin record thereon.

2. In a coin retainer, the combination of a pocket formed with enclosing flaps having 110 a coin slit; and a removable coin holder inserted in the pocket receiving coins from

the coin slit, said holder carrying the coins from the pocket as the holder is removed.

3. In a coin retainer, the combination of a pocket formed with enclosing flaps having a coin slit; a removable coin holder insertable in the pocket adapted to receive coins from the coin slit and to carry the coins from the pocket as the holder is removed; and a renewable seal for retaining the holder in the pocket.

4. In a coin retainer, the combination of a pocket formed with enclosing flaps having a coin slit; and a removable coin holder inserted in the pocket receiving coins from the coin slit, said holder carrying the coins from the pocket as the holder is removed, and having non-return flaps yieldingly permitting the movement of coin past the edge of the flap but obstructing a return movement past the edge of the flap.

5. In a coin retainer, the combination of a pocket formed with enclosing flaps having a coin slit; and a removable coin holder inserted in the pocket receiving coins from the coin slit, said holder carrying the coins from the pocket as the holder is removed, and comprising two folds, one of the folds having an inturned end receiving coin from the coin slit but preventing a return movement of the coin to the slit.

6. In a coin retainer, the combination of a pocket formed with enclosing flaps having a coin slit; and a removable coin holder inserted in the pocket receiving coins from the coin slit, said holder carrying the coins from the pocket as the holder is removed, and having opposing folds with inturned contacting ends forming an inward receiving passage for a coin entering the slit but preventing a return movement of the coin to the slit.

7. In a coin retainer, the combination of a pocket formed with enclosing flaps having a coin slit; and a coin holder insertable in the pocket adapted to receive coins from the coin slit and to carry the coins from the pocket as the holder is removed, said

holder having opposing folds with in-turned bends, one of the bends having its corner turned back to space it from one of the folds, said in-turned bends forming a passage leading from the slit to the holder permitting the insertion of a coin but preventing the return movement.

8. The combination of a removable pass book cover having opposing folds; a coin retaining pocket formed in one of the folds, said pocket having a coin receiving slot; and a removable non-return device arranged in the pocket receiving coins from said slot.

9. The combination of a removable pass book cover having opposing folds; a coin retaining pocket formed in one of the folds, said pocket having a coin receiving slot; and a removable holder in the pocket adapted to receive coins inserted into the pocket through the slot and to remove the coins so received as the holder is removed from the pocket.

10. The combination of a removable pass book cover having opposing folds; a coin retaining pocket formed in one of the folds, said pocket having a coin receiving slot; a removable holder in the pocket adapted to receive coins inserted into the pocket through the slot and to remove the coins so received as the holder is removed from the pocket; and a renewable seal for retaining the holder in the pocket and sealing the holder.

11. The combination of a removable pass book cover having opposing folds; a coin retaining pocket formed in one of the folds having a coin receiving slot; a removable holder in the pocket adapted to receive coins inserted into the pocket through the slot and to remove the coins so received as the holder is removed from the pocket; a renewable seal for retaining the holder in the pocket and sealing the holder; and a coin record on the renewable seal.

In testimony whereof I have hereunto set my hand.

EDWARD D. SMITH.
